UNITED STATES PATENT OFFICE.

HERBERT W. COOPER, OF MOLINE, ILLINOIS.

DESIGN FOR A HORSE-COLLAR FASTENER.

SPECIFICATION forming part of Design No. 25,488, dated May 12, 1896.

Application filed November 19, 1894. Serial No. 529,327. Term of patent 7 years.

To all whom it may concern:

Be it known that I, HERBERT W. COOPER, of Moline, in the county of Rock Island and State of Illinois, have invented and produced 5 a new and original Design for Horse-Collar Fasteners, of which the following is a specification.

The collar-fastener of my design is shown in the accompanying drawings, in which—

10 Figure 1 is a perspective view showing the under side of the fastener, and Fig. 2 is a top or plan view of the same.

The leading feature of my design consists in a horse-collar fastener having a body of 15 substantially triangular outline with rectangular depressions of unequal depth in its upper surface, cylindric apertures in the bottoms of alternate depressions, and truncated pyramidal enlargements or projections on the 20 lower surface of said body, the corners of said pyramidal portions being joined by curved lines.

In the drawings, A represents the body, which is substantially triangular in its general outline.

25 B and C represent rectangular depressions in the upper surface of said body, the depressions B being deeper than the depressions C and alternately arranged with reference thereto.

30 d represents cylindric perforations or apertures in the bottoms of the depressions C.

E represents enlargements or projections on the lower surface of said body, which are 35 of truncated pyramidal form, said pyramidal portions being joined by curved lines e.

I claim—

The design for a horse-collar fastener, substantially as herein shown and described.

HERBERT W. COOPER.
